E. Morris,
Slate Frame,

No 11,903.

Patented Nov. 7, 1854.

UNITED STATES PATENT OFFICE.

EDMUND MORRIS, OF BURLINGTON, NEW JERSEY.

SLATE-FRAME.

Specification of Letters Patent No. 11,903, dated November 7, 1854.

To all whom it may concern:

Be it known that I, EDMUND MORRIS, of the city and county of Burlington, State of New Jersey, have invented a new and Improved Mode of Making Slate-Frames, which invention consists in forming the frame out of a solid piece by sawing out the center and then cutting a kerf along and through each end of the frame, through

10 which kerf the slate may be inserted and adjusted in a groove previously cut to receive it on the inside of the frame, said kerf being afterward filled up by a tongue, the grain of which shall run in a direction contrary to the grain of the frame, said kerf answering the double purpose of admitting the slate and effectually strengthening the end of the frame.

A frame is made as follows, reference being had to the accompanying drawings.

20 A board of suitable thickness being sawed out, of the size of the slate frame desired, it is then placed over a vertical shaft a circular saw or other suitable cutter, which 25 forms the proper groove B, Figure A, on the inner sides of the frame, said shaft project-

ing through a table conveniently arranged for the purpose, and revolving the saw or cutter in a horizontal plane. The frame is then passed over a saw, which cuts in each end a kerf E, of the same width with the groove inside, and extending down to the dotted lines C, C. The slate is then passed through either of these end kerfs, adjusted in its place, the tongues C, C, Fig. 3, glued or otherwise secured in the kerfs, and the frame smoothed off. The tongues, by being made to extend down through the whole of the cross grain end of the frame, as shown by the dotted lines, effectually strengthen the frame.

Fig. D, represents a perfect slate; Fig. 3 shows the tongue, sawed out to fill up the kerf, and make a perfect fit.

What I claim is—

45 The mode of constructing a slate frame substantially as herein described.

EDMUND MORRIS.

In presence of—

WILLIAM C. MYERS,
MICHAEL SHEMELIA.
